AUTOMATIC SWITCH RECEPTACLE

Walter J. Schneider, La Grange, Ill.

Application September 27, 1938, Serial No. 231,970

8 Claims. (Cl. 200—38)

My invention relates to time controlled electric circuits and has among its objects and advantages the provision of an improved automatic switch receptacle.

5 An object of my invention is to provide an automatic switch receptacle designed for electrically connecting a source of current with electrically energized devices in which novel means are incorporated for closing and opening the electric 10 circuit at preselected times. The device embodies a novel switch mechanism actuated through the medium of a time device. The time device may comprise a conventional clock, and the automatic switch receptacle is so designed as to facilitate 15 connection with the time device in such manner as to provide a compact unit. Means are also provided to permit manual actuation of the switch independently of the time controlled mechanism.

20 In the accompanying drawings:

Figure 1 is an elevational view of my invention illustrating the clock end of the unit;

Figure 2 is a sectional view along the line 2—2 of Figure 1;

25 Figure 3 is a sectional view taken along the line 3—3 of Figure 1;

Figure 4 is a sectional view along the line 4—4 of Figure 3;

30 Figure 5 is a sectional view along the line 5—5 of Figure 3;

Figure 6 is a view illustrating the time setting feature with certain parts broken away for the sake of clearness;

35 Figure 7 is an elevational view of the switch on and off dials;

Figure 8 is a detail view illustrating the manner in which the time controlled mechanism operates to close the circuit;

40 Figure 9 is a sectional detail view of one of the manual controls;

Figure 10 is a perspective view of a latch mechanism; and

Figure 11 is a sectional view of a portion of the structure illustrated in Figure 8.

45 In the embodiment selected to illustrate my invention, I make use of a housing 10 which encloses the automatic switch receptacle mechanism 12. Adjacent one end of the housing 10 I mount a clock dial 14, which end of the housing 50 carries a glass 16 held in supporting relation with the flange 18 by a bezel 20. Figures 2, 4 and 5 illustrate the housing 10 as being provided with a floor 22 upon which the mechanism 12 is mounted as well as the clock motor 24, which 55 clock motor may be of the conventional design

employed in electric clocks. Housing 10, as well as the floor 22, may be formed of sheet metal. Upon the floor 22 I mount two upright walls 26 interconnected at their upper ends through the medium of a cross wall 28. The lower ends of 5 the walls 26 may be welded or otherwise secured to the floor 22.

Walls 26 are provided with bearings 30, see Fig. 11, which rotatably support a shaft 32. Upon the shaft 32 I rotatably mount discs 34 and 10 36. Disc 34 may be set for closing the circuit at a preselected time, while disc 36 may be set for bringing the switch opening mechanism into operation at a preselected time. Collars 38 on the shaft 32 hold the discs 34 and 36 in spaced relation. Referring to Figs. 2 and 11, an arm 40 is attached to the wall 28 and carries a short tube 42 at its lower end for housing a compression spring 44. Friction elements 46 are slideable inside the tube 42 and are urged outwardly by reason 20 of the compression spring 44 to restrain the discs 34 and 36 from accidental rotation upon the shaft 32. Friction elements 46 may be pointed on their outer ends, as illustrated in Fig. 11, with the pointed ends extending into grooves 48 in the 25 inner faces of the discs.

Discs 34 and 36 are provided with gears 50 and 52, respectively. Gear 50 is in mesh with a gear 54 formed integrally with a sleeve 56 to one end of which I mount an "on" dial 58. "On" dial 58 30 is provided with numerals 60 in the nature of a clock face for indicating periods of time. Gear 54 is provided with a bevel gear 62 arranged in mesh with a small bevel gear 64 fixedly connected with a shaft 66 rotatable inside a sleeve 68 made 35 secure to the wall 70 of the housing 10. Shaft 66 may be manually rotated through the medium of a knob 72 for setting the disc 34 for closing the switch at the selected time.

Rotation of the shaft 66 imparts rotation to the 40 gear 54, the sleeve 56 and the "on" dial 58. At the same time, such rotation will impart rotary motion to the disc 34. "On" dial 58 is located adjacent the clock face 14, which face is provided with a sight opening 74 for exposing the 45 numerals 60. Inside the sleeve 56 I rotatably mount a shaft 76 to one end of which I connect the "off" dial 78. "On" dial 58 is dished at 80 for housing the "off" dial 78, the face of the latter terminating flush with the numbered margin of 50 the dial 58. "Off" dial 78 is provided with numerals 82 arranged in the nature of a clock face for indicating periods of time. Numerals 82 may be read through the sight opening 74 in the same manner as the numerals 60, see Fig. 1. 55

To the opposite end of the shaft 76 I fixedly connect a gear 84 arranged in mesh with the gear 52 on the disc 36 and provided with a bevel gear 96 arranged in mesh with a small bevel gear 33 keyed to a shaft 90. Shaft 90 is rotatably supported by a sleeve 92 fixedly connected to the wall 70, and is provided with a knob 94 for turning purposes. Upright posts 96 constitute supports and bearings for one end of the sleeve 56 and the shaft 76, which posts may be welded to the floor 22. One post 96 is positioned adjacent the "on" dial 58 to restrain the sleeve 56 from longitudinal movement in one direction. Sleeve 56 is restrained from longitudinal movement in 15 the opposite direction because of the close relation between the dial 58 and the clock face 14.

Dial 78 has close fitting relation with the dial 58 so as to restrain the shaft 76 from relative longitudinal movement in one direction, while the 20 close fitting relation between the dial 78 and the clock face 14 prevents relative longitudinal movement in the opposite direction. Rotation of the shaft 90 imparts rotary motion to the dial 78 through the medium of the shaft 76, while such 25 rotation of the shaft 76 imparts rotary motion to the disc 36 for adjusting the same to open the switch at the preselected time.

Clock motor 24 drives a gear 93 fixed on a shaft 100 which carries a fixed gear 102 arranged 30 in mesh with a gear 104 fixedly related to the shaft 32. Shaft 32 rotates relatively to the discs 34 and 36. Upon the shaft 32 I mount a switch closing plate 106 which includes a sleeve 108 slidably longitudinally of the shaft. Sleeve 108 35 is integrally connected with the switch closing plate 106, and is slotted at 110 for the reception of a pin 112 fixed to the shaft. Slot 110 permits relative longitudinal movement of the sleeve 108 and its associated plate 106, but the pin 112 keys 40 the sleeve 108 to the shaft so as to connect the shaft and the sleeve for rotation as a unit.

Disc 34 includes a hub 114 provided with a notch 116, while the switch plate 106 carries a dog 118 shaped to fit in the slot 116. The angular face 120 of the dog 118 constitutes the leading face of the dog as the switch plate 106 is rotated through the medium of the clock motor 24. Thus the dog 118 will move suddenly into the notch 116 as the point of the dog is brought into registration with the notch. Such movement of the 50 switch plate 106 kicks the switch structure to its circuit closing position.

Means for shifting the switch plate 106 longitudinally of the shaft 32 as the dog 118 moves 55 into the notch 116 comprises a compression spring 122. Spring 122 is mounted on the sleeve 108 with one end positioned adjacent the switch plate 106 and its opposite end abutting a compression collar 124 slidably longitudinally of the 60 sleeve. Sleeve 108 rotates freely relatively to the collar 124. Collar 124 is grooved at 126 for loosely receiving a ring 128 provided with pins 130 constituting pivots for arms 132. Arms 132 are bowed and connected into a unitary structure, 65 as at 136, with an arm 138. Thus the arms 132 and the arm 138 provide a bell crank.

Arm 138 is pivotally connected at 140 to a bracket 142 secured to one of the upright walls 26. Tension springs 144 are connected with pins 70 146 anchored to the collar 124, and the opposite ends of the springs are anchored to the adjacent upright wall 26, as at 148. Springs 144 normally hold the collar 124 in the position of Fig. 3. In 75 this position of the collar 124, the compression spring 122 is substantially fully extended so as

to exert little pressure on the switch plate 106. In this position of the switch plate 106, the dog 118 may rotate freely relatively to the hub 114. Spring 122 is compressed for urging the switch plate 106 in the direction of the disc 34 by shift- 5 ing the collar 124 to the position of Fig. 3.

Referring to Figs. 8 and 10, one of the walls 26 carries two brackets 150 bored to slidably receive a push rod 152 extending through the wall 70 and provided with a knob 154 to facilitate 10 manipulation. The opposite end of the push rod 152 is provided with a hook 156 extending through a slot 158 in the arm 138 for actuating the bell crank. Brackets 150 are interconnected through the medium of a bar 160 provided with 15 spaced abutments 162 and 164. To the abutment 164 I fixedly connect a flat spring 166 by a screw 168, which spring extends across a cam finger 170 fixedly related to the push rod 152. Figure 8 20 illustrates the normal position of the push rod 152, at which time the cam finger 170 lies upon the ledge 172 of the bar 160 and adjacent the face 174 of the abutment 162.

Hook 156 includes a head 178 rotatable inside a socket 180 in one end of the push rod, see Fig. 9. Slot 158 in the arm 138 is of sufficient length to constitute a pivotal connection between the two parts in addition to permitting slight relative movement therebetween as the bell crank is pivoted from one position to the other. However, 30 slot 158 is of such limited proportions as to hold the hook 156 within the slot during relative rotary adjustment of the push rod 152. Push rod 152 may be shifted for bringing the cam finger 170 to the position of Fig. 10 through counter-clockwise rotation of the push rod against the tension of the spring 166 and an inward push on the rod sufficiently far to bring the finger 170 to the opposite side of the abutment 162, at which time the spring 166 presses the finger 170 40 downwardly.

Adjustment of the push rod 152 to the position of Figure 10 compresses the spring 122 by advancing the collar 124 in the direction of the switch plate 106, see Fig. 3. At the same time, 45 advancement of the collar 124 places the tension springs 144 under considerable tension. Collar 124 is latched in the position of Figure 3 because of the abutting relation between the cam finger 170 and the abutment 162. With the spring 122 50 compressed according to Figure 3, spring 122 exerts pressure on the switch plate 106 so as to throw the dog 118 into the notch 116 as the point of the dog is brought into registration with the notch. The point of the dog 118 has pressure re- 55 lation with the hub 114 and moves therealong, but the disc 34 is restrained from relative rotary movement on the shaft 32.

Bar 160 includes a right-angular bend 182 to which I pivotally connect a lever 184, as at 186. 60 Lever 184 is pivotally connected with the bend 182 intermediate its ends, and one end of the lever is pivotally connected at 188 with a link 190 having a hook 192 loosely fitting inside the groove 194 in the switch plate 106. Plate 106 is 65 free to rotate relatively to the hook 192.

To the opposite end of the lever 184 I pivotally connect a cam link 196, as at 198. Cam link 196 lies loosely in a groove 199 in the bar 172 and is provided with an angular end 200 arranged to 70 bear against the angular end 202 on the cam finger 170. Figures 8 and 10 illustrate the relation between the cam finger 170 and the cam link 196 with the push rod 152 pressed in. As 75 the shaft 32 is rotated through the medium of 95

the clock motor 24, the dog 118 will be brought into registration with the notch 116, at which time the switch plate 106 is kicked in the direction of the disc 34. As the switch plate 106 is kicked, the lever 184 is pivoted in the direction of the arrow 204 which advances the cam link 196 and elevates the cam finger 170 above the abutment 162. As the cam finger 170 is elevated above the abutment 162, the tension springs 144 return the collar 124 to the position of Figure 8. Such return of the collar 124 pivots the bell crank for pushing the rod 152 outwardly.

Referring to Figures 3 and 8, the switch is indicated generally at 206. Figure 3 illustrates the switch in its "off" position and Figure 8 illustrates the "on" position. The switch comprises an insulated body 208 provided with openings 210 for the reception of the prongs of a conventional plug electrically connected with the circuit 20 to be controlled. Contacts 212 are anchored in the body 208 and lie inside the openings 210 for connection with the prongs of the plug to be connected therewith. One of the contacts 212 is connected with a wire 214 extending through the body as at 216 for connection with a source of current. The other contact 212 is connected with a wire 218 electrically connected with a contact strip 220 pivotally connected at 222 to the body 208. Body 208 carries a contact 224 arranged to be engaged by the contact strip 220 and electrically connected with the second wire 226 for connection with the source of current. Contact strip 220 is pivotally connected at 228 with a bar 230 extending transversely of the body 208. Bar 230 is slidable longitudinally and has one end arranged to be engaged by the switch plate 106.

With the point of the dog 118 riding on the end of the hub 114, the switch plate 106 is held out of slightly spaced relation with the end of the bar 230, see Figure 3. As the dog 118 aligns with the notch 116, the spring 122 will kick the switch plate 106 in the direction of the disc 34. Such movement of the switch plate 106 will kick the bar 230 to the right, as when viewing Figure 3, for moving the contact strip 220 into contacting relation with the contact 224 to close the circuit.

To the contact strip 220, I connect one end of a tension spring 232, the other end of which is anchored to the body 208. With the contact strip 220 positioned according to Figure 3, the pivot 222 is located to one side of the spring so as to yieldingly support the contact strip in the position of Figure 3. When the bar 230 is kicked by the switch plate 106, the bar 230 is shifted to the position of Figure 8 for electrically relating the bar with the contact 224. With the contact strip 220 positioned according to Figure 8, the spring 232 yieldingly holds the contact in the position illustrated.

To the body 208 I pivotally connect a bell crank 234 at 236. One end of the bell crank is pivotally connected at 238 with the bar 230 and the other end of the bell crank is pivotally connected at 240 with a rod 242 extending through the wall 10 to be manually actuated through the medium of a knob 244. Thus the contact strip 220 may be manually actuated independently of the time controlled mechanism.

With the bar 230 positioned according to Figure 8, a second or opening switch plate 246 is positioned in close relation with the end of the bar. Switch plate 246 is identical with the switch plate 106 and includes a dog 248 arranged to drop

into the notch 250 in the hub 252 carried by the disc 36. Switch plate 246 includes the sleeve 254 slidable on the shaft 32 and keyed for rotation therewith in the same manner as the sleeve 108. The collar 256 is slidable on the sleeve 254 and is arranged to compress the spring 258 in the same manner as the collar 124. A bell crank 260 is pivotally connected at 262 to the bracket 264 and is operatively connected with the ring 266. Ring 266 is connected with tension springs 268 which 10 correspond to the tension springs 144.

Bell crank 260 is connected with the push rod 270, which rod extends through the wall 10 and is provided with a knob 272. Push rod 270 is slidable and rotatably supported by the brackets 15 274, and the rod carries a cam finger 276 pressed downwardly on the bar 278 by the flat spring 280. Bar 278 includes the right-angular bend 282 as well as an abutment 284 for latching the cam finger 276 in the position of Figure 3, which position 20 is more fully illustrated in Figure 10 which relates to the latch feature associated with the on switch plate 106. Bar 286 is pivotally connected at 288 with a cam link 290 cooperating with the cam finger 276 in the same manner as the cam link 196. Bar 286 is pivotally connected at 292 with the bend 282, and is pivotally connected at 294 with a link 296 having a hook 298 extending into the groove 300 in the switch plate 246. A tension spring 302 interconnects the arm 286 30 with the link 296 for holding the hook of the latter in the groove 300. Similarly, the lever 184 is interconnected with the link 190 by a similar spring 304 for holding the hook 192 in the groove 194. It will thus be seen that the off switch plate 35 246 is actuated through the medium of mechanism identical with that associated with the on switch plate 106.

Figure 8 illustrates the switch 206 in its on position at which time the bar 230 is arranged 40 to be kicked by the off switch plate 246 when its dog 248 drops into the notch 250. Such shifting of the switch plate 246 will kick the bar 230 and shift the contact strip to the off position, as illustrated in Figure 3.

Gear 104 includes a hub 306 provided with an axial bore 308 for the reception of the pintle 310 formed on the end of a shaft 312 which carries a gear 314 arranged in mesh with the gear 98. Pintle 310 is rotatable inside the bore 308, while 50 the shaft 312 extends loosely through a sleeve 316 and is connected with the minute hand 318. Sleeve 316 is rotatably supported by the dial 14 and is fixedly connected with a gear 320 arranged in mesh with a gear 322 keyed to the 55 shaft 100. The opposite end of the sleeve 316 is fixedly connected with the hour hand 324. Shaft 312, sleeve 316 in combination with the hands 318 and 324, respectively, are conventional clock parts. Dial 14 is provided with the usual time 60 divisions 326 illustrated in Figure 1.

An alarm mechanism 328 may be anchored to the dial 14 and is provided with a release 330 arranged in operative relation with a gear 332 arranged in mesh with the gear 310. Gear 332 is 65 slidable on a rotatable shaft 334 which rotatably carries a bevel gear 336. Gear 336 is arranged in mesh with a bevel gear 338 which may be rotated through the medium of a shaft 340 which may extend through the wall 10 in the same manner as the shafts 66 and 98. Gear 335 includes a hub 342 provided with a notch 344 arranged to receive the dog 346 carried by the gear 332. A spring 348 urges the gear 332 in the direction of the notched hub 342 for moving the gear 332 lon- 70 75

itudinally of the shaft 334 when the dog 346 aligns with the notch 344. When so aligned, the gear 332 will strike the alarm release 330 for setting the alarm in operation. The alarm mechanism may be manually shut off through the medium of a shaft 350 which may extend through the wall 70.

Shaft 334 is connected with the alarm hand 352 which alarm hand is associated with the 10 alarm dial 354 best illustrated in Figure 1.

From the foregoing description of the various parts of the device, the operation thereof will be readily understood. The clock mechanism may be set through the medium of a bevel gear 15 356 attached to the shaft 32. Bevel gear 356 is arranged in mesh with a small bevel gear 358 rotatable through the medium of a shaft 360. Shaft 360 may extend through the wall 70. To set the mechanism for actuating the switch 20 206 at a preselected time, the disc 34 is rotated through the medium of the shaft 96 for bringing the selected reading on the dial 58 into registration with the indicating mark 360 on the dial 14, see Figure 1. If it is desired to open the circuit at a preselected time, disc 36 is set through the medium of the shaft 90 for bringing the selected time reading on the dial 78 into registration with the indication 360. Clock motor 24 will drive the shaft 32 through the medium 30 of gear 88, shaft 100 and gears 102 and 104. Rotation of the shaft 32 rotates the switch plates 106 and 246. At the same time, the push rod 152 is rotated counter-clockwise for elevating the cam finger 170 over the abutment 162, and the 35 shaft is advanced for shifting the collar 124 from the position of Figure 8 to that of Figure 3. Push rod 270 is also set for advancing the collar 256. As the switch plate 106 is thrust in the direction of the disc 34, the bar 230 is struck by 40 the plate for shifting the contact strip 220 into electrical connection with the contact 224. At the same time, such shifting of the switch plate 106 pivots the lever 184 in the direction of the arrow 204 which elevates the cam finger 170 so 45 that the springs 144 will return the collar 124 to its normal position and reset the push rod 152.

The switch 206 will remain closed until the switch plate 246 has been rotated for bringing the dog 248 into registration with the notch 250. As the switch plate 246 is thrust in the direction of the disc 36, the switch plate strikes the bar 230 for kicking the contact strip 220 to its off position, as illustrated in Figure 3. Push rod 55 270 is released in the same manner as the push rod 152 so that the springs 268 will return the collar 256 to its normal position.

I claim:

1. In a device of the type described including 60 a clockwork rotated shaft, on and off members rotatably mounted on said shaft including means for individually adjusting said on and off members to preselected on and off positions, companion on and off members slidable on said shaft but keyed thereto for rotation therewith, a switch 65 including a switch element arranged to be selectively actuated by said companion on and off members for respectively closing and opening the switch, means cooperable on said on and off members and the companion on and off members for controlling the switch element actuating movement of said companion on and off members, and means for actuating said companion on and off members for operating said switch element.

2. In a device of the type described including a clockwork rotated shaft, on and off members rotatably mounted on said shaft including means for individually adjusting said on and off members to preselected on and off positions, companion on and off members slidable on said shaft but keyed thereto for rotation therewith, a switch including a switch element arranged to be selectively actuated by said companion on and off members for respectively closing and opening the 10 switch, means cooperable on said on and off members and the companion on and off members for controlling the switch element actuating movement of said companion on and off members, means for actuating said companion on 15 and off members for operating said switch element, concentrically arranged on and off dials, and coaxially arranged shafts operatively connected with the on and off members, respectively, for moving the dials when said on and off members are rotated on said shaft.

3. In a device of the type described including a clockwork rotated shaft, on and off members rotatably mounted on said shaft including means for individually adjusting said on and off members to preselected on and off positions, companion on and off members slidable on said shaft but keyed thereto for rotation therewith, a switch including a switch element arranged to be selectively actuated by said companion on and off 20 members for respectively closing and opening the switch, means cooperable on said on and off members and the companion on and off members for controlling the switch element actuating movement of said companion on and off members, normally inactive means for selectively actuating said companion on and off members for operating said switch element, and manually actuated means for selectively adjusting said normally inactive means to active positions.

4. In a device of the type described including a clockwork rotated shaft, on and off members rotatably mounted on said shaft including means for individually adjusting said on and off members to preselected on and off positions, companion on and off members slidable on said shaft but keyed thereto for rotation therewith, a switch including a switch element arranged to be selectively actuated by said companion on and off members for respectively closing and opening the 50 switch, means cooperable on said on and off members and the companion on and off members for controlling the switch element actuating movement of said companion on and off members, normally inactive means for selectively actuating said companion on and off members for operating said switch element, manually actuated means for selectively adjusting said normally inactive means to active positions, and means for selectively returning said normally inactive means to inactive 55 positions after actuation of their respective on and off members.

5. In a device of the type described including a clockwork rotated shaft, on and off members rotatably mounted on said shaft including means for individually adjusting said on and off members to preselected on and off positions, companion on and off members slidable on said shaft but keyed thereto for rotation therewith, a switch including a switch element arranged to be selectively actuated by said companion on and off members for respectively closing and opening the switch, means cooperable on said on and off members and the companion on and off members for controlling the switch element actuating 70

movement of said companion on and off members, means for actuating said companion on and off members for operating said switch element, said on and off members each including a gear, concentrically arranged on and off dials, and coaxially arranged shafts each connected with one of said dials and geared to one of said gears for operatively connecting the on and off dials with the on and off members, respectively.

- 0 6. In a device of the type described including a 10 clockwork rotated shaft, on and off members rotatably mounted on said shaft including means for individually adjusting said on and off members to preselected on and off positions, companion on and off members slidable on said shaft but keyed thereto for rotation therewith, a switch including a switch element arranged to be selectively actuated by said companion on and off members for respectively closing and opening the 15 switch, means cooperable on said on and off members and the companion on and off members for controlling the switch element actuating movement of said companion on and off members, normally inactive spring means for selectively actuating said companion on and off members, and manually actuated means for selectively placing said spring means under tension for actuating the 20 companion on and off members, and means for shifting said spring means to inactive positions after actuation of said companion on and off members.
7. In a device of the type described including a 25 clockwork rotated shaft, on and off members rotatably mounted on said shaft including means for individually adjusting said on and off members to preselected on and off positions, companion on and off members slidable on said shaft but keyed thereto for rotation therewith, a switch 30 including a switch element arranged to be selectively actuated by said companion on and off members for respectively closing and opening the switch, means cooperable on said on and off members and the companion on and off members for controlling the switch element actuating movement of said companion on and off members, means for actuating said companion on and off members for operating said switch element, said switch element comprising a pivoted member having a bar positioned between said companion on and off members for selective engagement thereby.

tively actuated by said companion on and off members for respectively closing and opening the switch, means cooperable on said on and off members and the companion on and off members for controlling the switch element actuating movement of said companion on and off members, normally inactive spring means for selectively actuating said companion on and off members, manually actuated means for selectively placing said spring means under tension for actuating the 10 companion on and off members, and means for shifting said spring means to inactive positions after actuation of said companion on and off members.

8. In a device of the type described including a 15 clockwork rotated shaft, on and off members rotatably mounted on said shaft including means for individually adjusting said on and off members to preselected on and off positions, companion on and off members slidable on said shaft 20 but keyed thereto for rotation therewith, a switch including a switch element arranged to be selectively actuated by said companion on and off members for respectively closing and opening the switch, means cooperable on said on and off members and the companion on and off members for controlling the switch element actuating movement of said companion on and off members, 25 means for actuating said companion on and off members for operating said switch element, said switch element comprising a pivoted member having a bar positioned between said companion on and off members for selective engagement thereby.
